COMBINATION SLIDE CALIPER AND PROTRACTOR

Alfred Robbins, 136 W. 54th St., New York, N.Y.

Filed Mar. 8, 1960, Ser. No. 59,660

Term of patent 14 years

(Cl. D52—6)

FIG. 1

FIG. 2

FIG. 3

FIG. 4

FIG. 1 is a side elevational view of a combination slide caliper and protractor showing my new design.

FIG. 2 is an elevational view of the opposite side thereof.

FIG. 3 is a left end elevational view of FIG. 1.

FIG. 4 is a right end elevational view of FIG. 1.

I claim:

The ornamental design for a combination slide caliper and protractor, as shown.
